UNITED STATES PATENT OFFICE.

CHARLES A. GREEN AND HENRY F. SCHUH, OF CHICAGO, ILLINOIS, ASSIGNEES TO
THE C. F. PEASE COMPANY, OF CHICAGO, ILLINOIS, A CORPORATION OF ILLINOIS.

RULING PEN.

1,421,455.

Specification of Letters Patent.

Patented July 4, 1922.

Application filed December 29, 1919. Serial No. 348,177.

To all whom it may concern:

Be it known that we, CHARLES A. GREEN and HENRY F. SCHUH, citizens of the United States, residing at Chicago, in the county of 5 Cook and State of Illinois, have invented certain new and useful Improvements in Ruling Pens, of which the following is a specification.

This invention relates to new and useful 10 improvements in ruling pens and more particularly to that type of ruling pen wherein one blade is so connected that it may be swung in the open position for cleaning.

An important object of the invention is to 15 provide means whereby the tension applied against the butt of the swinging blade of the pen may be adjusted.

A further object is to provide a pen of this 20 type wherein the parts are readily assembled and disassembled.

Other objects and advantages will be apparent through the course of the following description.

In the accompanying drawings wherein 25 for the purpose of illustration is shown a preferred embodiment of my invention and wherein like numerals designate like parts throughout,

Figure 1 is a side elevation partly in section of a ruling pen embodying our invention.

Figure 2 is a view similar to that shown in Figure 1, the swinging blade being elevated.

35 Figure 3 is a combined view of the working parts of the pen, and

Figure 4 is a section taken on the line 4-4 of Figure 2.

Referring now more particularly to the 40 drawings, the numeral 10 indicates a stationary blade. Pivoted to the stationary blade as at 11, is a swinging blade 12 provided at its butt with a cam face 12^a. The swinging blade 12 is provided with an adjusting screw 13 of the usual type.

The butt end of the stationary blade 10 is provided with a bore and is internally threaded as at 14 to receive a screw 15 having a central bore 16. The screw is provided 45 with a screw driver receiving notch 17 by means of which it may be adjusted within the butt end of the stationary blade 10.

Mounted within the bore 16 of the screw 50 is a coiled compression spring 18. A plunger pin 19 is provided having a reduced

portion 19' forming a shoulder 20. The reduced portion 19' is adapted to be received interiorly of the coil of the compression spring 18 and the main body of the plunger pin 19 slidably fits the bore 16 of the screw 15. 60

The outer end of the plunger pin 19 is provided with an enlarged head 21 which is forced into engagement with the cam face 12^a of the swinging blade 12 by the action of the spring 18. It will be seen that by adjusting the screw 15 within the stationary blade 10, the pressure applied to the swinging blade 12 by means of the plunger pin 19 may be adjusted. This feature is extremely desirable in that the tension placed upon the 70 swinging blade 10 regulates the amount of force which must be applied to turn the adjusting screw 13 by means of which the swinging blade 12 is adjusted with relation to the stationary blade 10. As is well known 75 to those familiar with the art no two draftsmen prefer the same tension for the swinging blade. Furthermore, the screw 17 may be readily removed and the spring 18 and plunger pin 19 removed therefrom for the 80 purpose of cleaning to remove collected ink and the like. India ink hardens rapidly and very often interferes with the proper operation of the pen.

A ferrule 22 is provided having an internally threaded bore 23 adapted to receive the projecting end of the screw 15. The opposite end of the ferrule is provided with an externally threaded portion 24 adapted to receive the handle 25 of the pen. If desired the ferrule 22 may be entirely dispensed with and the handle 25 attached directly to the stationary blade by means of the projecting end of the screw 15. It will be seen that the screw 15 not only provides tension adjustment, but also serves as a means for connecting the blades and the handle. 90 95

As many changes are possible in the shape, size, and arrangement of the various parts herein shown and described, we do not limit 100 ourselves to the specific structure herein set forth, but may make any such changes without departing from the spirit of the invention or the scope of the subjoined claims.

What we claim is:

1. In a ruling pen, a stationary blade having a threaded bore in its butt end, a swinging blade pivotally connected with said stationary blade adjacent said bore and provided adjacent its pivot with a cam face, a member 105 110

mounted within the bore, a compression spring within the bore projecting said member for engagement with said cam face and an externally threaded member extending 5 within said bore and engaging the spring and having its upper end extending outwardly from the butt end of said stationary blade to provide means for attaching a handle.

10 2. In a ruling pen, a stationary blade having a threaded bore in its butt end, a swinging blade pivotally connected with said stationary blade adjacent said bore and provided adjacent its pivot with a cam face, a 15 member having a central bore and provided with external threads engaging the threads of the bore of said stationary blade, a compression spring mounted in the bore of said member, and a plunger mounted in the bore 20 of said member and pressed by said spring into engagement with said cam face.

3. In a ruling pen, a stationary blade having a threaded bore in its butt end, a swing-

ing blade pivotally connected with said stationary blade adjacent said bore and provided adjacent its pivot with a cam face, a member having a central bore and provided with external threads engaging the threads of the bore of said stationary blade a coiled compression spring mounted in the bore of 30 said member, and a plunger mounted in the bore of said member and pressed by said spring into engagement with said cam face, said plunger having a portion slidably fitting said bore, a reduced portion extending 35 centrally of the coils of said spring and an enlarged head adapted to engage said cam face.

In testimony whereof we affix our signatures in presence of two witnesses.

CHARLES A. GREEN.
HENRY F. SCHUH.
